(57) **CLAIM**

The ornamental design for a display screen with a transitional graphical user interface, as shown and described.

DESCRIPTION

FIG. 1 is a front view of a first image in a sequence for a display screen with a transitional graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of a eighth image thereof; FIG. 9 is a front view of a ninth image thereof; FIG. 10 is a front view of a tenth image thereof; FIG. 11 is a front view of a eleventh image thereof; FIG. 12 is a front view of a twelfth image thereof; FIG. 13 is a front view of a thirteenth image thereof; FIG. 14 is a front view of a fourteenth image thereof; FIG. 15 is a front view of a fifteenth image thereof; FIG. 16 is a front view of a sixteenth image thereof; and, FIG. 17 is a front view of a seventeenth image thereof. The outermost broken line rectangle illustrates a display screen and forms no part of the claimed design. The remaining broken lines illustrate portions of the graphical user interface and form no part of the claimed design. All shading illustrates a contrast in appearance and forms part of the claimed design.

(Continued)

The appearance of the image sequentially transitions between images shown in FIGS. 1 through 17. The process or period in which one image changes to another forms no part of the claimed design.
